SPARK PLUG

Harold J. Muir, Chicago, Ill., assignor to Animated Spark Plug Company, Chicago, Ill., a corporation of Illinois

Application September 8, 1930, Serial No. 480,378

3 Claims. (Cl. 123—169)

This invention relates to improvements in spark plugs, particularly of the type for employment in internal combustion engines and while the invention is described and illustrated as incorporated 5 in a type of spark plug having one insulated terminal and a grounded sparking terminal complementary thereto, it will be understood that the invention may be applied to other types of spark plugs and that it, therefore, finds a wide field 10 of utility.

The principal objects and advantages of this invention reside in the provision of an improved type of spark plug wherein improved means for admitting cleansing and cooling air to the vicinity 15 of the sparking terminals of the electrodes is provided; the provision of an improved form of spark plug in which fresh air or atmospheric air is admitted to the vicinity of the sparking terminals for increasing the degree of combustion and 20 thereby preventing accumulation of carbon and other fouling matter thereon; the provision of an improved spark plug and means for admitting atmospheric air at the vicinity thereof in an engine cylinder, in combination with means for preventing backfiring through the spark plugs; the 25 provision of an improved spark plug of the type referred to wherein fresh air or atmospheric air is permitted to enter adjacent to the sparking terminals but is excluded from direct contact upon 30 entry with the insulating element or elements so as to prevent undue heating and thereby disintegration of the insulating element.

This invention has, as a further object, the provision of an improved means of the character referred 35 to which is capable of application either to spark plugs having a single insulated terminal or to spark plugs in which both terminals are insulated from the casing or shell of the plug, and wherein the application of this invention may be 40 had without changing the particular spark plug in size as to outside dimension so that the article when produced according to this invention is of a substantially standard size and external contour thereby obviating the necessity for special tools 45 or special fittings to permit of its commercial adaptation to existing internal combustion engines and the like.

The foregoing and such other objects and advantages as may appear or be pointed out as this 50 description proceeds are attained in the structural embodiment of the invention illustrated in the accompanying drawing in which:

Figure 1 is a longitudinal sectional view through a spark plug including the improvements 55 of this invention; and

Figure 2 is a transverse sectional view of the same taken on the line 2—2 of Figure 1, looking in the direction indicated by the arrows.

Referring now more particularly to the drawing, wherein a preferred embodiment of this invention is illustrated, I provide a metallic casing or shell 5. This casing or shell is provided with a bore 6 formed with a shoulder 7 and the outer internally threaded portion 8. The outer end thus internally threaded is externally polygonally 60 formed as indicated at 9 to permit of the application of a wrench for inserting the spark plug into a combustion chamber or into the cylinder head of an internal combustion engine. The casing 5 is provided with a cylindrical portion 10 which is 65 externally threaded as at 11 to facilitate engagement of the spark plug in a suitably threaded opening in the internal combustion engine, usually provided in the cylinder head thereof.

The cylindrical wall of portion 10 also serves 70 to support the so-called grounded electrode 12 which is fixed in a suitable aperture longitudinally of the wall 10 and projects toward the axis of the cylindrical bore 6 as is the conventional construction of spark plugs.

A central or axial insulated electrode 13 is provided and mounted in an insulating support 14 which may be constructed of any suitable heat resisting insulating material such as pressed asbestos, mica, porcelain, or the like. The insulating support 14 is substantially cylindrical throughout substantially half of the length thereof and is annularly enlarged as at 15 to seat upon a suitable metallic packing ring 16 mounted on the shoulder 7.

A retaining gland nut 17 is in engagement with the internal threaded portion 8 by the provision of a cylindrical extension 18, the nut having an annular internal flange 19 engaging the outer end of the enlargement 15 and thus impinging said 90 enlargement on the packing 16 and fixedly retaining the insulating supporting member against rotative and longitudinal displacement and at the same time forming a fluid-tight joint; that is, a joint which will prevent the escape of gases 95 from the combustion chamber.

I find that in a spark plug made according to my invention, a greater intensity of heat is present immediately adjacent to the electrodes due to the admission of oxygen in the air passing to the 105 vicinity of the sparking terminals and, therefore, find it desirable to mount the insulated electrode 13 in the supporting member 14 so that the unequal expansion and contraction of these elements will not cause fracture of the insulating 110

support. To this end, the electrode 13 extends upwardly through the support 14 into an enlarged extension member 20 which projects beyond the upper end of the insulating support to form an insulating post 21 on which a retaining nut 22 is threaded. The outer end of the electrode 13 is received in a bore 23 provided in the threaded extension 20 and is fixed therein by soldering or any other desirable means, the electrode and said extension 20 being retained and sealed in position in the support 14 by the introduction of a heat resistant and insulating cement 24. This physical contact or connection between the electrode 13 and the insulating support 14 is limited to a point adjacent to the outer end of the electrode 13 thus affording a space 25 between the electrode and the insulating supporting member 14 thereby permitting the expansion and contraction of the electrode without fracture of the insulating support or chipping of the same at its narrowed tapered end indicated at 26. The space 25 afforded is of limited degree so that for all useful purposes the electrode is well supported substantially throughout its entire length.

25 In order to facilitate combustion, keep the electrodes and the insulating member relatively cool and to prevent pitting of the electrodes and the collection of carbon and other deposits on the spark plug terminals, I provide at least one air duct or passageway in the cylindrical wall 10, it being understood that any reasonable number of these ducts may be provided without departing from the spirit of the invention. The drawing shows two such ducts, 27 and 28, and two controlling means therefor. As the ducts 27 and 28 and their respective controlling means are identical, I will describe but one of the same.

The duct 27 has an outlet 29 to the combustion chamber adjacent to the sparking terminals 12 and 13 and admits air to this vicinity, but excludes air upon entry from direct contact with the tapered portion 26 of the insulating support. The duct 29 extends up through the cylindrical wall 10 and terminates in an enlarged external annular flange 30 which is intended to abut the outer wall of the cylinder head when the plug is inserted into position. The duct or passageway 27 thus communicates with an inner recess 31 extending radially of the spark plug casing or shell and located within said annular flange.

50 The recess 31 is adapted to receive and contain a check valve element 32 having a seat 33 and a stem 34 projecting through an aperture 35 in a valve cage 36, which latter is provided with a suitable valve seat and extends into the recess 31 to retain the check valve in position and to form a seat member therefor.

It will be observed that the inner cylindrical portion 37 of the cage 36 is left plain both as to its periphery and as to its end edge 38 so that it forms a firm seat in the inner end of the recess 31.

55 It will be understood that upon each reciprocating motion of the piston in the internal combustion engine, which has been omitted from this drawing, the check valves will be opened and closed to afford entry of fresh air at atmospheric temperature to the vicinity of the sparking terminals. Owing to the intense heat thus generated, I have found it desirable that the air thus admitted be deflected away from the insulating supporting member rather than directly upon it as this not only will crack the insulating member but actually will reduce it in some cases to 75 a molten state, particularly where the spark

plug is employed in the so-called high-pressure type of automobile engine where high-test fuel is regularly employed.

It will be understood by those skilled in the art that, due to the intensifying of the spark and the resultant heat generated, brought about by the admission of fresh air, at the vicinity of the spark, and the proximity of the narrower or tapered portion of the insulator to this locality, and coupled with the increase above normal of the distortion of the electrode (expansion and contraction), fracture of the insulator at this point is imminent, but applicant by spacing the electrode for most of its length from the wall of the opening in the insulator, or conversely supporting it from a relatively small area, air is permitted to circulate within the opening, thus cooling the insulator and the electrode and, therefore, at no time can the unequal expansion or contraction of the electrode and insulator produce unequal stresses therein and fracture or chipping from these causes is thus substantially eliminated.

I claim:

1. In a spark plug, an outer conducting shell 100 or casing and a sparking terminal carried by the inner end thereof in operative position, an insulating member in said shell having a tapering inner end and provided with an axial opening, an electrode supported near one end in and of less diameter than that of said opening and extending beyond the inner tapered end of said insulating member so as to be free to expand and contract without contact with the major portion of said opening, means for admission into and discharge of fresh air only to the vicinity of said sparking terminal and away from the inner end of said insulating member for intensifying the spark produced thereby, the space between said electrode and the wall of said opening permitting circulation of air therein for cooling the insulating member, and the free mounting of said electrode permitting expansion and contraction of said electrode and insulator without producing destructive stresses in said insulating member, thereby preventing fracture of the insulator adjacent to said tapered end.

2. In a spark plug, an outer shell or casing and a sparking terminal carried thereby, an insulating member in said shell provided with an axial opening, an electrode supported in and of less diameter than that of said opening, said electrode extending beyond the inner end of said insulating member adjacent to said sparking terminal, means for admitting fresh air to the vicinity only of said sparking terminal and away from the inner end of said insulating member for intensifying the spark, and means near the outer end of said opening for engagement with a relatively small area of said electrode so that the same is supported in spaced relationship to the wall of the opening over a relatively large portion of its area, and thereby permitting expansion and contraction or other distortion of the electrode, due to the admission of fresh air adjacent to said sparking terminal and to thereby prevent fracture or chipping of said insulating member at its inner end, without interference by said insulating member.

3. In a spark plug, in combination, an outer 145 conducting shell or casing externally threaded and adapted for attachment to a complementally threaded aperture in the combustion chamber of an internal combustion engine, a sparking terminal carried in operative position by the 150

inner end of said conducting shell or casing, an insulating core member in said shell having a tapered inner end and provided with an axial opening, an electrode of less diameter than that 5 of said opening supported within said opening only at the outer end of said opening, thus providing an annular space between said electrode and said insulating core member permitting the circulation of air therein for cooling the insulating core member, and the free mounting of said electrode permitting expansion and contraction of said electrode and said insulating core member independently of each other, thus preventing fracture of said insulator member due to 10 destructive stresses set up by unequal expansion and contraction of different materials, said electrode also extending substantially beyond the inner end of said insulating core member to remove the point of maximum temperature from 15 the immediate vicinity of the inner end of said core; and means, entirely contained within the walls of said shell or casing whereby fresh air is admitted through the walls of said casing at each stroke of said engine, said means comprising a longitudinal passageway in the walls of said casing having access to atmosphere outside of the engine and a valve member at the outer end of said passageway permitting passage of air into said passageway due to suction in said combustion chamber but closing said passageway under compression in said combustion chamber, said passageway extending so that the air is admitted only at the inner end of said spark plug in the vicinity of said sparking terminal away 20 from the end of said insulator for the purpose of intensifying the spark and causing more complete combustion in said combustion chamber. 80 85 90
